[57] CLAIM

The ornamental design for a gasoline pump nozzle lever brace, as shown and described.

DESCRIPTION

FIG. 1 is an elevational view of the upper end of a gasoline pump nozzle lever brace showing my new design;

FIG. 2 is a left side elevational view thereof;

FIGS. 3 and 4 are respectively bottom and top plan views thereof;

FIG. 5 is an elevational view of the lower end thereof; and,

FIG. 6 is a right side elevational view thereof.
